STILL CAMERA

Samuel F. Swayze, Rochester, N.Y., assignor to Eastman
Kodak Company, Rochester, N.Y.

Filed Jan. 13, 1972, Ser. No. 217,723

Term of patent 14 years

Int. Cl. D16—01

U.S. Cl. D61—1 B

FIG. 1

FIG. 2

FIG. 3

FIG. 4

FIG. 5

FIG. 1 is a top and front perspective view of a still camera showing my new design with the lens cover closed; FIG. 2 is a bottom and rear perspective view thereof; FIG. 3 is a front perspective view thereof with the lens cover opened;

FIG. 4 is a front perspective view of a second embodiment of my new design wherein an electronic shutter sensor has been added to the front panel; and

FIG. 5 is a front perspective view of a third embodiment of my new design wherein an electronic shutter sensor and a close-up switch have been added to the front and top thereof.

I claim:

The ornamental design for a still camera, as shown and described.
